United States Patent Office.

HEINRICH FLINSCH, OF FRANKFORT, PRUSSIA.

Design No. 4,626, dated February 7, 1871.

DESIGN FOR TYPE.

The Schedule referred to in these Letters Patent and making part of the same.

To all whom it may concern:

Be it known that I, HEINRICH FLINSCH, of the city of Frankfort-on-the-Main, State of Prussia, Germany, type-founder, have invented or produced a new style of Printing-Type for Letter-press Printing of a new and original design, which I describe as follows, viz: "Condensed Aldine."

They are of a kind known to the trade as "Titles," (see annexed printed impression of characters,) and of the size usually known as Great Primer, but this title differs from all others in style, proportion, shape, peculiarity of ceriphs.

I call this new type "Condensed Aldine;" and I claim—
The design of the type, as described and shown in the "Characters" of the accompanying printed sheets. This specification signed by me this 28th day of November, 1870.

HEINR. FLINSCH.
